UNITED STATES PATENT OFFICE

GENEVIEVE BRUER, OF SAN FRANCISCO, CALIFORNIA

GARMENT BOX

Application filed December 10, 1928. Serial No. 324,938.

My invention relates to garment containers and may be embodied either in a shipping box of cardboard construction or in an article of luggage such as a suit-case or the tray of a trunk.

The principal object of my invention is to provide a garment container having a member adapted to hold the garment in proper shape to prevent creasing, which can be manufactured and sold at such low cost as to permit it to be used as a temporary package for the delivery of garments and to be thrown away thereafter. A second object is to provide a container having a garment holding member which can, if it be so desired, be removed with the garment and hung up, serving as a hanger for the garment after its removal from the box. A still further object is to provide a garment container which can be made of cardboard and shipped flat in knocked down form and which, when so made, will cost only very slightly more, for both manufacture and shipping, than the ordinary cardboard box now commonly used for the delivery of garments.

These and other objects and advantages of the invention will be apparent from the following description, which should be read with the understanding that the form, construction and arrangement of the several parts may be varied, within the limits of the claims hereto appended, without departing from the spirit of the invention as defined therein.

A preferred embodiment of my invention will now be described with reference to the accompanying drawings, wherein:

Fig. 1 is a plan view of a complete garment box.

Fig. 2 is a longitudinal section taken on the line 2—2 of Fig. 1.

Fig. 3 is a perspective view of the garment holding member removed from the box.

In the drawings, the reference numeral 1 designates a box, which may be either an ordinary cardboard garment box as used for delivery purposes, or an article of luggage such as a suit-case or trunk-tray, or any other kind of a box of suitable shape for holding a garment. Within the box 1 is fitted a garment

holding member 2, which I prefer to make from a flat sheet of cardboard, as shown in Fig. 3. Its upper end (the right hand end as seen in the drawings) is turned down at right angles, as shown as 3, and rests upon the bottom of the box against one end thereof. The turned down end 3 is preferably the full width of the box, in order to provide lateral stability without positive connection with the end of the box.

Immediately below the upper end, the holder 2 is formed with notches or cut-outs 4 in its sides. The lower edges or corners 5 formed by said notches receive the shoulders of the garment (not shown) the collar thereof lying beneath and partially encircling the neck 6 formed between said notches. The lower end 7 of the holder 2 is folded back upon itself along a line adjacent the end of the box, as shown at 7', the lower portion of the garment being folded over therewith.

The length of the holder 2 when folded, as shown in Fig. 2, is approximately the same as the inside length of the box. It is preferably made of light material, such as cardboard, having considerable resilient flexibility, so that it may bend or curve in the middle to shorten its effective length if a bulky garment is folded over its lower end. Such bending of the holder causes it to hold the garment, resiliently but firmly, against the lower end of the box, thereby preventing shifting. The lower folded end 7 may be omitted, in which case the holder would terminate at the fold 7'.

Although it is not essential, I prefer to make the notches 4 substantially V-shaped, with their upper edges parallel to the end of the holder and in line with the fold 3' of the turned down upper end. This causes said fold to occur at the narrowest portion of the neck 6, and makes it easy to locate.

The upper end of the holder 2 is preferably provided with an eye or grommet 8, Fig. 3, in which a wire hook 9 may be placed. This allows the holder with the garment thereon to be removed from the box and hung in a closet or wardrobe, serving as a hanger for the garment.

It will readily be appreciated that the

holder 2 can be made easily and cheaply, by stamping from light cardboard, and when so made, can be shipped flat with the ordinary form of knocked down cardboard box in which it is to be used, thus adding very little to the cost of such a box, and the entire package, both box and holder, may be discarded after a single use. If intended for use in an article of luggage, however, the holder may, if desired, be made of more lasting material.

It will also be seen that the holder, when used in a garment containing box of suitable size, not only preserves the shape of the garment, by holding its shoulders in position, and keeping them elevated above the bottom of the box, but also, by extending from end to end of the box, keeps even a light garment such as a woman's dress in its position in the box, preventing shifting and bunching when the box is roughly handled. Moreover, by fitting closely within the box, both sideways and endways, and having no other connection with the side walls thereof, the entire body of the holder 2 forms a support for the garment when the box is stood upon its end or side.

I claim:—

1. A garment holder adapted for free positioning in a box comprising a flat member having notches in its side edges near one end adapted to receive the collar of the garment, the end portion of said member above said notches extending the full width of the box and being turned downwardly to rest upon the bottom thereof.

2. A garment holder adapted for insertion in a box comprising a flat member having notches in its side edges near one end adapted to receive the collar of the garment, the end portion of the member adjacent said notches extending the full width of the box and being turned downwardly to rest upon the bottom thereof, and the opposite end portion of said member being folded back upon itself along a line adjacent the end of the box.

In testimony whereof I have signed my name to this specification.

GENEVIEVE BRUER.
